MIRRORED LIPSTICK CASE

Don Eliot, Glendale, Calif., assignor to Merle Norman Cosmetics, Inc., Los Angeles, Calif., a corporation of Nevada

Filed Dec. 5, 1966, Ser. No. 4,921

Term of patent 14 years

(Cl. D86—10)

FIG. 1.

FIG. 2.

FIG. 4.

FIG. 3.

FIG. 5.

FIG. 1 is a front perspective view of a mirrored lipstick case showing my new design.

FIG. 2 is a side elevation view;

FIG. 3 is a rear elevation view;

FIG. 4 is a top plan view; and

FIG. 5 is a bottom plan view.

I claim:

The ornamental design for the mirrored lipstick case, as shown and described.
